UNITED STATES PATENT OFFICE.

FRANK DOMOWITCH, OF WILKES-BARRE, PENNSYLVANIA.

SPARK-ARRESTER.

1,112,364.

Specification of Letters Patent. Patented Sept. 29, 1914.

Application filed April 14, 1914. Serial No. 831,885.

To all whom it may concern:

Be it known that I, FRANK DOMOWITCH, a citizen of the United States, residing at Wilkes-Barre, in the county of Luzerne and State of Pennsylvania, have invented a new and useful Spark-Arrester, of which the following is a specification.

This invention relates to spark arresters, one of its objects being to provide simple, 10 efficient and compact means housed completely within the smoke box of the locomotive and whereby sparks and cinders are trapped before reaching the smoke pipe and are retained at a point where they can be 15 conveniently reached and removed.

A further object is to provide an arrester which will not interfere with the draft through the boiler.

With the foregoing and other objects in view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

In the accompanying drawings the preferred form of the invention has been shown.

In said drawings: Figure 1 is a view partly in elevation and partly in section through a portion of a locomotive boiler having the present improvements combined therewith, the spark arrester being shown in side elevation. Fig. 2 is a vertical section through a portion of a locomotive boiler and showing the spark arrester in section. Fig. 3 is a section on line A—B Fig. 2. Fig. 4 is a section on line C—D Fig. 2.

Referring to the figures by characters of reference 1 designates a portion of a locomotive boiler having a smoke box 2 at one end as ordinarily, this smoke box being provided 45 with the usual smoke pipe 3 and with the exhaust nozzle 4.

Depending from the smoke box close to the head 5 of the boiler is a cinder box 6 having a movable bottom 7. A segmental partition 8 is arranged transversely within the smoke box close to and parallel with the head 5, this partition bridging the cinder box 6. A segmental baffle plate 9 is suspended within the upper portion of the smoke box and extends downwardly a short distance below the upper edge of the partition 8 and is

spaced from said partition, any suitable means being provided for this purpose. Another segmental partition 10 is arranged within the smoke box and is preferably parallel with the partition 8, this partition 10 being extended upwardly from one wall of the cinder box 6 and being provided, along its upper edge, with a depending inclined apron 11 discharging downwardly into a trough 12 which extends transversely of the smoke box and has its bottom inclined downwardly to a discharge spout 13.

The space between the partitions 8 and 10 is divided by a partition 14, into compartments 15 and 16, the said compartment 16 receiving the cinders discharged from the spout 13 while the compartment 15 receives any cinders which may be carried downwardly between partition 8 and baffle plate 9. The upper portion of partition 14 is inclined laterally and upwardly, as shown at 14' while the lower or substantially vertical portion of the partition 14 laps a partition 17 which extends downwardly into the cinder box 6. An inclined screen 18 extends from the upper edge of the hopper 12 to the top of the smoke box and overhangs the partition 10.

It will be apparent that when the products of combustion issue from the boiler 1, they will be deflected by the partition 8 and baffle plate 9 and pass downwardly as indicated by the arrow in the drawings so that sparks and cinders will thus be directed 85 downwardly into the compartment 15 and fall into the cinder box 6. The gases and lighter particles will flow outwardly over the partition 10 and through the screen 18, any sparks and cinders coming into contact 90 with the screen being deflected downwardly and guided by the apron 11 into the hopper 12. From this hopper the said cinders, etc., will gravitate into compartment 16 and thence into the box 6. By opening the bottom of the cinder box the contents of said 95 box can be removed.

It will be seen that a device such as herein described constitutes efficient means for stopping sparks and cinders so that they will 105 not be ejected through the pipe or stack 3. Furthermore, the device will not retard the circulation of the combustion products to an undesirable extent. By having the partition 8 bridge the box 6, any portion of the 110 combustion products which may be deflected downwardly will be free to pass into the

box 6 and thence upwardly between the two partitions 8 and 10.

What is claimed is:

1. The combination with the smoke box 5 of a boiler, of a spark arrester therein and extending into the path of the combustion products, said spark arrester including a cinder box, spaced partitions above the cinder box, and spaced at their upper edges 10 from the top of the smoke box, a baffle depending from the top of the smoke box and between the partitions, a hopper, a screen extending from the hopper to the top of the smoke box and intersecting the path of the 15 products of combustion from between the partitions, the said hopper discharging into the space between the partitions.

2. The combination with the smoke box of 20 a boiler, of a spark arrester including a cinder box, transverse partitions within the smoke box and above the cinder box, said partitions being spaced from the top of the smoke box, a baffle plate depending from the top of the smoke box and between the partitions, a hopper supported by one of the partitions, a screen extending from the hopper to the top of the cinder box and across the path 25 of the products of combustion flowing from between the transverse partitions, said hopper discharging into the space between the partitions, and a partition connecting the trans-

verse partitions and dividing the space therebetween into separate compartments opening downwardly into the cinder box.

3. The combination with the smoke box 35 of a boiler, of a spark arrester including a cinder box depending from the smoke box and having a bottom adapted to be opened, spaced transverse partitions above the cinder box, a partition connecting the said 40 transverse partitions and dividing the space therebetween into upper and lower compartments discharging downwardly into the cinder box, a baffle plate depending from the top of the smoke box and between the 45 transverse partitions, an apron extending downwardly from one of the transverse partitions, a hopper for receiving material from the apron, said hopper discharging into the lower compartment between the partitions, 50 and a screen extending from the hopper to the top of the smoke box and intersecting the path of the products of combustion issuing from the compartment.

In testimony that I claim the foregoing 55 as my own, I have hereto affixed my signature in the presence of two witnesses.

FRANK DOMOWITCH.
